CORD EXTENSION DEVICE

Richard C. Wittman, Emporium, Pa.

Application August 7, 1946, Serial No. 688,889

5 Claims. (Cl. 242—47.5)

1

This invention relates to new and useful improvements in extension cord holders and has especial reference to a device for use in connection with cords of the nature of electric cords and air hoses used in garages and may also be used for water and gas hoses for the furnishing of air and gas to owners of automobiles.

The invention constitutes an improvement over my previous Patent No. 2,280,680 and an object of the invention is to provide a simple and more efficient arrangement of pulleys to double the possible extension with the same distance of travel of the pulley carriage as well as to increase the ease with which the device may be operated.

A further object is to provide a simple and efficient device in which the slideable pulleys can be moved along their track with a minimum of effort and friction, and maintain their proper relation at all times.

A further object is to provide a device in which the parts may be disposed for proper operation regardless of the angularity of the wall or surface to which they may be attached.

Further and more specific objects, features and advantages will more clearly appear from a consideration of the specification hereinafter set forth especially when taken in connection with the accompanying drawings which illustrate a present preferred form which the invention may assume and which form part of the specification.

In brief and general terms the invention includes a frame comprising upper and lower brackets adjustably disposed with respect to the supporting surface, a pair of guide elements supported by and extending between the brackets, two fixed pulleys at the top of the frame, two slideable pulleys at the lower portion of the frame and slideably related to the guide elements and means to enable the movable pulleys to engage the guide elements with a minimum of friction. To facilitate ease of operation and reduce strain on the cord, rope, or hose all the pulleys mentioned are disposed and move in the same plane.

More particularly the device includes a pulley frame supporting two pulleys, and related to the guide rods or pipes, the pulley frame having pairs of rollers disposed on opposite sides of each pipe to bear against the same and permit sliding movement of the frame up and down the pipes with minimum friction while keeping the pulley frame in proper angular relation at all times.

The present preferred form which the invention may assume is illustrated in the drawings of which,

2

Fig. 1 is a side elevation of the device;

Fig. 2 is a plan view of the device;

Fig. 3 is a side elevation of the travelling pulley carriage;

Fig. 4 is a plan view of said carriage;

Fig. 5 is a cross section taken on the line 5—5 of Fig. 3;

Fig. 6 is a cross section taken on the line 6—6 of Fig. 3;

Fig. 7 is a cross section taken on the line 7—7 of Fig. 3 showing the weight plates attached; and,

Fig. 8 is a perspective view of one of the weight plates.

The present preferred form of the invention is shown in the drawings and comprises a simple and efficient means for supporting a flexible cord 10 such as an electric cord or air hose used in garages, or any other flexible connector. This cord 10 is adapted to pass over two fixed pulleys 11 and 12 and over two movable pulleys 13 and 14 all of which are disposed in the same plane. These pulleys are associated with a supporting frame construction which comprises U-shaped bracket members 15 and 16 made of formed strips

25 of metal and the top and bottom of the device. The upper bracket has an extension 17 to support the pulley 11 whereas the lower bracket 16 has no such extension. Between the brackets 15 and 16 extend the vertical guide members 18 and 19 in the form of pipes. These pipes are rigidly held in connection with the brackets 15 and 16 in the corners thereof by being welded in place.

To the opposite sides of the pipes is welded a bar 20 from the top of which rearwardly extends a flat metal extension strip 26 having a hole 27 through which the cord 10 passes and in which it may be fastened by any suitable positioning means (not shown).

The extension bracket 17 is adjustably fastened to the main bracket 15 by means of bolts 22 and 22'. The latter also connect the main bracket 15 with supporting legs 39 and act as points around which the bracket 15 may be swivelled with respect to the legs 39 so that the legs may be set to meet the wall 23 squarely even when said wall is not vertical. The legs 39 are suitably bolted to the wall 23.

The outer pulley 11 is supported between the side plates of the extension bracket 17 in any desired manner. The other fixed pulley 12 is supported on a bolt or shaft 24 passing through the pipes 18 and 19 just below the upper bracket

15. Spacer sleeves 25 are employed to properly dispose the pulley in position. On each side of the pulley 12 are disposed circular shaped guard

plates 21 the free ends of which are fastened to the bar 20 and the base of the bracket 15 is shown in Fig. 2. These guards prevent the cord from slipping off the pulley 12. It is to be noted that the lower bracket 16 supporting the lower ends of the pipes 18 and 19 are connected to the pipes in a similar manner to that above described and is connected to lower legs similar to the legs 39 so that they may be connected to the wall in the same manner.

The two lower movable pulleys 13 and 14 are mounted on shafts 28 and 29 journaled between frame plates 30 and 31. At their mid-portions these plates have vertical straps 32 and 33 with upper and lower portions provided with stub shafts such as 34 supporting pairs of roller 35 on opposite sides of the respective guide pipes 18 and 19. In this manner the frame supporting the lower pulleys is held in proper angular position at all times while being able to slide up and down the pipes 18 and 19 with a minimum of friction regardless of the angular disposition of the pipes. It is also to be noted that the upper and lower ends of the straps 32 and 33 are bent outwardly as at 40 (see Fig. 5) so as to limit the movement of the frame within the pipes 18 and 19 in a plane at right angles to plane of movement in which the frame is limited by the rollers 34 and 35. Therefore the frame is guided and limited in its movement in two right-angled planes as described so that its movement is regulated and the frame is always held within limits as to any movement except along the pipes 18 and 19. The frame plates 30 and 31 are provided with a series of holes 36 to receive screws or bolts whereby extra weight plates 38 may be attached to the outside of the plates 30 and 31 whenever it is desired to increase the weight of the sliding frame for the lower pulleys. As shown in Figs. 4 to 7 inclusive, the lower pulleys may have spacing washers 31 disposed to maintain them spaced from rubbing against the frame plates 30 and 31 if desired.

In the operation of the device, the brackets 15 and 16 are adjusted as desired with respect to the surface 23. At the upper portion of the device are the two fixed pulleys and at the lower portion of the device are the two movable pulleys; slideable along the guide elements or pipes and provided with means to enable this sliding motion to take place with a minimum of friction and the greatest of ease and to allow twice as much cord to be extended for a given movement of the pulleys frame as in previous devices. The weight of the slideable frame can be varied by means of auxiliary weight plates to be added to or taken from the frame as desired. The fact that the pulleys are all disposed and move in the same plane permits easier operation with less strain on the parts and with practically no lateral thrust due to the hose passing from one plane to another.

This construction gives a simple, effective unit which enables the cord to have much greater extension, holds it in proper position without snarling and yet allows it to be pulled out with ease in view of the nature of the multi-pulley arrangement. It also permits a much longer cord extension and allows movement of the pulley frame with ease and without jamming.

While the invention has been described in detail and with respect to a present preferred form which the invention may assume, it is not to be limited to such details and form since many changes and modifications may be made in the

invention without departing from the spirit and scope of the invention in its broadest aspects. Hence it is desired to cover any and all forms and modifications of the invention which may come within the language or scope of any one or more of the appended claims.

What I claim as my invention, is:

1. A device of the class described which includes upper and lower brackets disposed on a supporting surface, a pair of guide elements supported by and extending between said brackets and spaced from said surface, two fixed pulleys disposed at the upper portion of the device, a pair of slideable pulleys disposed at the lower portion of the device, all of said pulleys disposed and movable in the same plane, a frame supporting said slideable pulleys, and means on the frame to engage the guide elements to hold the frame in proper angular position.
2. A device of the class described which includes upper and lower brackets disposed on a supporting surface, an extension to the upper bracket, a pulley fixedly disposed on said extension, a pair of guide elements supported by and extending between said brackets, a second pulley fixedly disposed between said guide elements near the top thereof, a pulley frame disposed between said guide elements, a pair of pulleys disposed on said frame, all of said pulleys disposed and movable in the same plane, roller means on said frame and arranged in pairs to engage opposite sides of each guide element to guide the frame in its sliding movement up and down between said elements.
3. In a device of the class described; a U-shaped bracket plate, a pair of guide elements disposed in the corners of said U-shaped plate, a bar connected to the opposite sides of said guide elements, an extension strip on said bar and extending toward the open end of the U-shaped plate, said extension strip having an aperture to receive a cord to be supported.
4. In a device of the class described, which comprises upper and lower brackets, a pair of guide elements extending between said brackets, a pulley fixedly disposed between said guide elements near the top thereof, curved strip like guard plates disposed on opposite sides of said pulley, said guard plates supported from the upper bracket and said guide elements.
5. In a device of the class described which includes upper and lower brackets, a pair of guide elements extending between said brackets, a pulley frame disposed between said guide elements, roller means on said frame and arranged in pairs to engage opposite sides of each guide element to limit the motion of the frame in one plane, and outwardly bent flanges on said frame to extend toward the inner surfaces of said guide elements to limit the movement of said frame in another plane at right angles to the first mentioned plane.
